Primary Examiner — S. Bryan Reinholdt, Jr.*Assistant Examiner* — Kaitlan Walker(74) *Attorney, Agent, or Firm* — Warner Norcross + Judd LLP(57) **CLAIM**

The ornamental design for optical sight reticle as shown and described.

DESCRIPTION

FIG. 1 is a view of the optical sight reticle embodying the new design;

FIG. 2 is an enlarged detail view of area 2 circumscribed in FIG. 1; and,

FIG. 3 is a perspective view showing an environment of use for the optical sight reticle of FIGS. 1-2.

The evenly spaced broken lines depict portions of the optical sight reticle that form no part of the claimed design. The evenly spaced broken circular outermost perimeter line in FIG. 1 depicts both portions of the optical sight reticle and the boundary of the claim that forms no part thereof. The broken lines in FIG. 3 depict environment that forms no part of the claimed design. The dot-dash broken lines depict the boundaries of the detailed enlargement that form no part of the claimed design.
